(57) **CLAIM**

The ornamental design for a handle for use with fan towel, as shown and described.

DESCRIPTION

FIG. 1 is a perspective view of a handle for use with fan towel showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof shown in its environment;

FIG. 9 is a close-up view of the first connection piece thereof; and,

FIG. 10 is a close-up view of the second connection piece thereof.

The dashed lines in the figures illustrate the portions of the design that form no part of the claimed design. The dash dot lines depict environmental subject matter only and form no part of the claimed design. None of the broken lines form any part of the claimed design.
